UNITED STATES PATENT OFFICE.

WALTER H. SCHUSSLER, OF PHILADELPHIA, PENNSYLVANIA, ASSIGNOR TO UNIVERSAL TOBACCO MACHINE COMPANY, OF NEWARK, NEW JERSEY, A CORPORATION OF NEW YORK.

CIGAR-BAND FEEDING AND MOISTENING MACHINE.

Application filed January 29, 1924. Serial No. 689,224.

The invention relates in general to machines for delivering to the place of application, or in applying moistened bands, labels and the like to articles such as cigars, 5 cigarettes, bottles and in general any device to which a band or label is to be applied and more particularly to improvements in machines for feeding bands from a stack or source of supply, moistening them, and delivering them to a definite position where a cigar is laid on top of the band, in a determined relation to the band. The operator then applies the band to the cigar and seals the ends of the band.

One object of the invention is to provide 15 a machine of the character described embodying a novel and improved construction, wherein the support for the bands, labels etc. is arranged directly under a suction band carrying drum, said suction drum holding the band in position and carrying it into position for securing it about a cigar, thereby eliminating any other transfer devices for the band, which effects a saving in 20 time and consequent economy in the operation.

In the preferred form of the invention, the band support is arranged beneath a suction drum so that the uppermost band of 30 the pile may be lifted by suction from the pile, and retained in correct position on the drum, which position is determined by the relative position of the band support and suction drum.

Another object is to provide a machine of 35 this character including novel and improved means for adjusting the band guides for bands of different dimensions.

Another object is to provide a novel and 40 improved construction for operating the band support, and novel means for moistening the band.

It further comprehends novel band feeding mechanism which feeds the bands one at 45 a time into position for the operator to apply them to the articles, and novel means for moistening an end of the bands during the feeding operation.

Other novel features of construction and 50 advantage will hereinafter more clearly appear in the detailed description and the appended claims.

For the purpose of illustrating the inven-

tion, I have shown in the accompanying drawing a typical embodiment of it, which, 55 in practice, will give reliable and satisfactory results. It is however to be understood that this embodiment is typical only and that the various instrumentalities of which my invention consists can be variously arranged 60 and organized, and that the invention is not limited to the precise arrangement and organization of these instrumentalities as herein set forth.

Figure 1 is a front elevation of a cigar 65 band feeding and moistening machine, embodying my invention.

Figure 2 is a side elevation with the front frame removed.

Figure 3 is a top plan view.

Figure 4 is a top plan view, with the table top removed.

Figure 5 is a section on line 5—5 of Figure 4.

Figure 6 is a fragmentary sectional elevation 75 in the moistening finger and band holder.

Figure 7 is a fragmentary side elevation of moistening finger and suction drum.

Figure 8 is a plan view of the moistening 80 device.

Figure 9 is a longitudinal section of the suction drum.

Figure 10 is a fragmentary top view of 85 the inner drum.

Figure 11 is a top plan view of band feeding and moistening cam levers.

Figure 12 is a side elevation on line 12—12 of Figure 11.

Figure 13 is a section on line 13—13 of 90 Figure 11.

Figure 14 is a similar view to Figure 13 but showing parts in a different position from that seen in Figure 13.

Figure 15 is a top plan of the band sup- 95 port and certain of its adjuncts.

Figure 16 is a section on line 16—16 of Figure 15.

Figure 17 is a front elevation of the band 100 magazine support.

Figure 18 is a side elevation of a band guide.

Similar numerals of reference indicate corresponding parts.

Referring to the drawings: 105
The specific embodiment of the invention

shown in the drawings includes side frames 1, which are connected together by front tie bars 2, and rear tie bars 3. 4 is a driving belt, for applying motion to a pulley 5, 5 said pulley being secured to a shaft 6, which shaft is journaled in the side frames 1. Mounted on said shaft and secured thereto, is a band feeding and moistening cam 7 and a drum feed cam 8. Secured to the frames 10 1 is a cam lever shaft 9, and loosely mounted on this shaft is a band frame and moistening cam lever 10 and a band feeding cam lever 11. Secured to the shaft 9 is a pawl release lever 12. 13 is a drum feed cam lever which 15 is free to oscillate on the shaft 9. Secured to the lever 10, and forming a part thereof is an arm 14. 15 is a roller pin secured in bearings in the arms 10 and 14. Mounted loosely on this pin is a cam roller 16. 17 20 is a spring stud secured to the arm 14. 18 is a spring, one end of which is secured to the pin 17, and its other end is secured to the pawl 19, which is free to revolve on a pin 20 secured to the arm 14. The pawl 19 25 co-operates with ratchet teeth 21, which are a part of the lever 11. The same pawl 19 is released from engagement with said ratchet teeth 21 by a cam face 22 which is a part of the lever 12. 24 is a spring stud 30 secured to the lever 10. 25 is a spring, one end of which is secured to a pin 24, and the other end of which is secured to a pin 26, which latter is fast to the frames 1. 27 is a spring stud secured to the lever 11. 28 35 is a spring the ends of which are secured to pins 27 and 29. The pin 29 is fast to the frames 1. 30 is a cam face on the lever 10. 31 is a cam face on the lever 11. 32 is a cam roller which is free to revolve on a stud 33 40 which latter is secured to an arm 34 of the lever 13. Secured to the lever 13 is a stud 35 on which is free to move a link 36. The other end of this link is free to move on a pin 37, said pin being secured to a lever 38. 39 is a spring stud secured to the frame 1. 40 is a spring, one end of which is secured to a pin 39, and the other end of such spring is secured to a pin 37. The lever 38 is free to move on a stationary shaft 41 45 secured to the frames 1. 42 is a pin secured to the lever 38. Free to move on the pin 42, is a ratchet pawl 43. 44 is a spring, one end of which is connected to a pin 46 secured to the pawl 43, and the other end of said spring is secured to a lug 45 which is a part of the lever 38. 47 is a driving ratchet for a suction drum 48 and is secured to it. 49 is a 50 detent roller, free to move on a pin 50 which is secured to a lever 51, free to move on a stud 52, which latter is secured to the frames 1. 53 is a spring pin secured to the lever 51. 54 is a spring pin secured to the frames 1. 55 is a spring connecting studs 53 and 54. The suction drum 48 has suction ports 56 in 55 its outer periphery. This suction drum 48 revolves on an inner drum 57, which is secured to the shaft 41 and is composed of a half circular frame 58, see Figures 9 and 10. The suction chamber of the inner drum has suction ports 59 in its wall 60, a suction chamber 61, and a suction outlet 62. 63 is a lug which is a part of the inner drum 57. 64 is a water container secured to the frames 1, by screws 65 and pins 66. 67 is a shaft rotatable in bearings which are a part of the water container frame. Mounted on a shaft 67 is a band retainer or clamp 68 which is free to move on the shaft 67. Also mounted on the shaft 67 is a spring 69, one end of which is secured to the shaft, and the other end of which is lapped behind the clamp 68. 70 is a moistener pad secured to an arm 71 which is fixed to the shaft 67. 72 is a roller free to move on a pin 73, which is secured to a lever 74, said lever being secured to the shaft 67. 75 is a band support carrier free to slide up and down on the rear frame 1. Screws 76 hold the carrier 75 in place and pass through slots 77. 78 is a spring pin secured to the band carrier 75. 80 is a spring pin secured to frames 1. 79 is a spring, one end of which is secured to a pin 80 and the other end of which is secured to the pin 78. 81 is a roller, free to rotate on a stud 82, which is secured to the band support carrier 75. 83 is a fulcrum pin, mounted in bearings on the band support carrier 75. Mounted on this pin and free to move on it is a band support 84. Secured to this support is a spring pin 85. 86 is a spring pin secured to the carrier. A spring 87 connects pins 85 and 86. Sliding in the upper part of the band support 84, is a rod 88 having a platform or table 89 secured to it. This rod 88 has a guide slot 90 through which passes a screw 91. 92 is a roller free to move on a pin 93, which is secured to the rod 88. 94 are adjustable band guides which are adjustable in slots 97 of the support 84. 95 are clamp screws for guides 94. These guides have a catch 96 at their top. 98 are adjustable side band guides secured to gear wheels 99, said wheels being free to rotate on studs 100, which are secured to the support 84. 101 are adjusting worms which mesh with one of each set of gear wheels. This worm is free to rotate in a bearing 102 of the support 84, and has secured at its outer end a knob 103. 104 is a fulcrum stud secured to the rear frame 1. Mounted loosely on this stud is a stop lever 105. This lever contacts with lugs 106 of the lever 10, at notch 107. 108 is a table top secured to the frames 1. Mounted on this table top 108, and forming a part of it are lugs 109. 110 are band passages cut in the table top 108. 111 is an adjustable end stop for a cigar 112. This stop is supplied with a slot 114, and has a locking screw 113. 115 are side guides or stops for the cigar 112, and have slots 116

117, and the guides are secured in adjusted position by locking screws 116. 118 is a cigar band, see Figure 3. 119 is a stop lug on the carrier 75. 120 is a stop lug on the support 84, and 121 is another stop lug to limit outward movement of the support 84. 122 is a detent spring secured to a lug 123 which is a part of the band support 84.

The operation is as follows:

10 The operator moves the band support 84 from the position seen in full lines in Figure 1 to that seen in dotted lines in said figure and stacks the bands one above the other on the platform 89. At the same time, he 15 moves the platform 89 and its rod 88 downwardly thus turning the lever 11 on its fulcrum against the tension of its spring 28, see Figures 2 and 11. The operator now releases the support 84 and its spring 87 returns said support to the position seen in 20 full lines in Figure 1. We will now assume that the main driving shaft 6 is revolving and that the feed controlling arm 105 is interlocked with the lug 106, see Figure 2, so 25 that the spring 25 is ineffective to move upwardly the lever 10 and permit the upward movement of the band support, the roller 81 of which contacts with said lever. Assuming now that the operator is ready for the 30 feeding of the bands or labels, he moves the controlling feed arm 105 outwardly to disengage it from the lug 106 so that the spring 25 will cause the upward movement of the lever 10 when such upward movement is permitted by the cam 7 fixed to the driving shaft 6 to revolve in unison with it.

The spring 79 tends to move the carrier 75 upwardly when the lever 10 moves upwardly and brings the guides 94 and 98 into contact 40 with the periphery of the suction drum 48, as the lever 10 moves upwardly the arm 14 moves upwardly, see Figures 11 to 14 inclusive, thus causing the cam 22 to move the pawl 19 out of engagement with the teeth of 45 the ratchet 21 which is a part of the lever 11.

A continuous suction is maintained within the suction drum so that the top band of the stack is retained on the periphery of the drum 48.

50 As the lever 10 moves upwardly it raises the arm 74, see Figure 12, to rock the shaft 67, and cause the presser 68, see Figure 5, to move towards the suction drum 48, so that the previous band, which, by the partial rotation of the suction drum has been positioned above the presser, will be firmly held against the drum when the presser is in its upward position. The presser 68 is loose on the shaft 67, but is raised by the spring 69 one end of which is fixed to the shaft, thereby permitting the moistening pad 70 to contact with the adhesive carrying portion of the band after the upward movement of the presser. The moistening pad is carried by 65 the shaft 67 to move in unison with it. As

the pad 70 moves downwardly the presser 68 prevents the band being stripped from its aligned position on the suction drum. When the lever 10 is moved downwardly by its cam, the shaft 67 and its adjuncts return 70 to their normal positions due to gravity. As the lever 10 moves downwardly the pawl 19 interlocks with the teeth of the ratchet 21 thereby causing the downward movement of the lever 11, so that the platform 89 moves 75 downwardly and the stack of bands is moved downwardly below the zone of the suction.

The downward movement of the lever 10 causes it by means of the roller 81 to move downwardly the band support 84 and its 80 carrier 75 into the position seen in Figure 2.

The cam 8 is fixed to the driving shaft 6 to cause the lever 13, at this time, to rock and move forwardly the link 36, to move the arm 38, which carries the pawl 43, so that the 85 ratchet 37 is moved, and thereby the drum 48 to which it is fixed, one step. A suction port 56 above the bands is now uncovered. The detent 51 prevents rearward movement of the suction drum. The lever 13, link 36, 90 arm 38 and pawl 43 are returned to their normal position by the spring 40 when permitted by the position which the cam 8 has assumed.

The suction drum is thus intermittently 95 revolved to successively bring the moistened bands 118 into applying position as shown in Figure 3. The band is retained on the suction drum 48 but its free ends have been 100 raised by the lugs 109, so as to be more readily grasped by the operator.

The operator now places a cigar between the guides 115 and against the end guide 111. The operator now takes hold of the free ends of the band and seals them 105 together about the cigar. The banded cigar is then removed and the cycle of the operation is repeated. The driving shaft 6 is driven by any desired source of power. The pipe 62 is connected with any desired source 110 of suction supply. The band guides 98 can be independently adjusted, as shown in Figure 15, to accommodate bands of different dimensions by actuating the worms 101. The band guides 94 are independently adjustable and are locked in position by screws 115 95, see Figures 16 and 18. The pad 70 when in raised position presses a band against a stationary lug 63 which forms an abutment.

It will now be apparent that I have devised a new and useful cigar band feeding and moistening machine which embodies the features of advantage enumerated as desirable in the statement of the invention and the above description, and while I have, in the present instance, shown and described a preferred embodiment thereof which will give in practice satisfactory and reliable results, it is to be understood that this embodiment is susceptible of modification in 120 125 130

various particulars without departing from the spirit or scope of the invention or sacrificing any of its advantages.

Having thus described my invention, what I claim as new and desire to secure by Letters Patent, is:

1. In a band feeding mechanism, an article support having an opening a rotatable suction drum, means to feed bands thereto, means to moisten the bands while retained on the drum, and actuating means for said drum to bring a band thereon through said opening.
2. In a band feeding mechanism, an article support having an opening a rotatable suction drum, means to feed bands thereto, means to moisten the bands while retained on the drum, actuating means for said drum to bring a band on the drum through said opening and means to deflect the free ends of a band when in cigar applying position.
3. In a band feeding mechanism, a rotatable suction drum, a band support, resilient means to move said band support towards said drum, means to move said band support away from said drum, means to moisten the bands, and actuating means for said drum.
4. In a band feeding mechanism, a rotatable suction drum having suction ports, means to feed bands thereto, a rock shaft, a presser loosely mounted thereon, a spring to effect relative movement of said presser and shaft, and actuating means for said suction drum.
5. In a band feeding mechanism, a rotatable suction drum having suction ports, means to feed bands thereto, a rock shaft, a presser loosely mounted thereon, a spring to effect relative movements of said presser and shaft, band moistening means actuated by said rock shaft, and actuating means for said suction drum.
6. In a band feeding mechanism, a rotatable suction drum, a band carrying support, means to effect relative movement of said drum and said support, moistening mechanism for the bands, presser mechanism to retain the bands in proper alignment on the drum during the moistening operation, and actuating means for said drum.
7. In a band feeding mechanism, a rotatable suction drum, a band support, a lever co-operating therewith, a tension device for said lever, a cam to move said lever and permit relative movement of said band support and said suction drum, and actuating means for said drum.
8. In a band feeding mechanism, a rotatable suction drum, a band support, a lever

co-operating therewith, a tension device for 60 said lever, a cam to move said lever and permit relative movement of said band support and said suction drum, means to retain said lever in its inoperative position and thereby prevent the feeding of bands to said drum, 65 and actuating means for said drum.

9. In a band feeding mechanism, a rotatable suction drum, an article supporting table having an opening through which the bands are brought, guides to position an 70 article on said table, means to feed bands to said drum, and actuating means for said drum.

10. In a band feeding mechanism, an article support having an opening through 75 which the bands are brought, a suction member adapted to successively move the bands through said opening and having suction ports, a band support, guides rotatably adjustable on said support, and means to effect 80 relative movement of said member and said band support to bring the bands into the zone of suction of said member.

11. In a band feeding mechanism, an article support having an opening through 85 which the bands are brought, a suction member to successively move the bands through said opening and having suction ports, a band support, guides rotatably adjustable on said support, and means to effect relative movement of said member and said band support to bring the bands into the zone of suction of said member, and relatively adjustable end guides on said band support.

12. In a band feeding mechanism, an article support having an opening through which the bands are brought, a suction member to move the bands through said opening having suction ports, a band support, 100 guides rotatably adjustable on said support, and means to effect relative movement of said member and said band support to bring the bands into the zone of suction of said member, and means to retain said band 105 guides in their adjusted position.

13. In a band feeding mechanism, an article support having an opening through which the bands are brought, means on said support in proximity to said opening to 110 cause the free ends of the bands to be deflected upwardly, a suction drum, means to feed bands thereto, means to moisten the bands and means to actuate said drum to cause the bands carried thereby to be 115 brought through the opening of said article support.

WALTER H. SCHUSSLER.
